DEVICE FOR APPLYING YIELDING PRESSURE
TO A TOP ROLL IN A DRAWING FRAMEThadeus J. Giemza, Whitinsville, Mass., assignor to
Whitin Machine Works, Whitinsville, Mass., a corpo-
ration of Massachusetts

Application December 11, 1953, Serial No. 397,696

2 Claims. (Cl. 19—135)

This invention relates to drawing frames in which wool or other similar yarn is drafted.

It is the general object of this invention to provide an improved device for applying yielding pressure to a movably mounted top roll in a drawing frame.

To the attainment of this general object, I provide spring-operated pressure-applying means which may be conveniently placed in operative position and as conveniently removed therefrom without displacing associated parts.

My invention further relates to arrangements and combinations of parts which will be hereinafter described and more particularly pointed out in the appended claims.

Preferred forms of the invention are shown in the drawings, in which

Fig. 1 is a front elevation of parts of a drawing frame having my improvements assembled therewith;

Fig. 2 is a sectional end elevation, taken along the line 2—2 in Fig. 1;

Fig. 3 is a perspective view of my improved pressure-applying device;

Fig. 4 is a fragmentary perspective view showing a slight modification; and

Fig. 5 is a plan view, partly in section, of the type of anti-friction top roll with which the construction shown in Fig. 4 would be associated.

Referring to Fig. 1, I have shown parts of a drawing frame of commercial type and including upper and lower driven rolls 10 and 11 rotatably and slidably mounted in bearing brackets or supports 12 and extending into a head 14. The head 14 contains mechanism for rotating the rolls 10 and 11 and also for reciprocating or traversing the rolls relative to the fixed bearing support 12. It will be understood that the support 12 is duplicated at spaced points throughout the length of the drawing frame.

A traverse rod 16 is slidable in the supports 12 and is connected at 17 to the head 14 for reciprocation therewith. Double top rolls 20 are associated with spaced drafting portions 21 and 22 of the drawing rolls 10 and 11.

The specific mechanism for rotating and traversing the rolls 10 and 11 forms no part of the present invention, and suitable mechanism for this purpose is disclosed in the patent to Kooistra, No. 1,973,534 issued September 11, 1934.

My improved device for applying pressure to the top rolls 20 comprises a rigid metal frame member 30, preferably of aluminum, which frame member has slots 31 in its lower portion to receive lugs 32 formed on a part 33 which is mounted on the traverse rod 16 and may be secured thereto by a set-screw 35. The position of the part 33 on the traverse rod 16 determines the position of the frame member 30 along the axis of the drawing rolls 10 and 11.

The frame member 30 has a forwardly-extending arm 40 which is slotted at its outer end to receive studs 42 in a bell-crank lever 44. A depending arm 45 of the lever 44 supports a bearing block 46 which engages the middle portion or neck 47 of the double top roll 20. The bearing block 46 may be of nylon or other similar anti-friction material.

A finger loop 48 on the front side of the arm 45 may be utilized for relieving pressure on a top roll 20, should removal thereof be desired.

The frame member 30 has an intermediate partition 50

with a positioning lug 51 which centers the lower end of a pressure-applying spring 52. The bell-crank lever 44 has a rearwardly-extending arm 55 provided with a depending lug 56 which receives and centers the upper end of the spring 52.

With this construction, the spring 52 applies a desired yielding pressure to the double top roll 20 through the bell-crank lever 44 and bearing block 46. Bearing members 60 of nylon or other similar anti-friction material are formed to snap over the rolls 10 and 11, and these members may be loosely mounted on the front side of the frame 30. Each block 60 may be provided with a stud 61 and may be held from displacement by a cotter-pin 62.

The rearward thrust of the spring 52 against the neck 47 of the top roll 20 will thus be offset by the supporting action of the bearing blocks 60.

With this construction, a desired spring pressure is applied to each double top roll 20, and each pressure-applying unit or device may be mounted in position or removed therefrom without interference with any other part of the machine.

All parts of my invention are of light-weight and easily constructed, and the device may be very readily applied to different commercial drawing frames.

For some purposes, it is desirable to use anti-friction top rolls of the type shown in Fig. 5, in which shells 70 are mounted on ball-bearings 71 carried by a short shaft 72 having a neck portion or recess 73. As this shaft 72 is not driven and commonly does not rotate, the bearing block 46 (Fig. 3) may be replaced by the simple bracket 75 shown in Fig. 4. Otherwise the construction and operation is as previously described, the arm 45a and the loop 48a corresponding in all respects to the arm 45 and the loop 48 previously described.

The traverse rod 16 and part 33 may be omitted, in which case the rolls 10 and 11 are provided with recesses similar to 73 (Fig. 5) to accommodate the bearings 60 and position the frame 30 axially of the drawing rolls 10 and 11.

Having thus described my invention and the advantages thereof, I do not wish to be limited to the details herein disclosed, otherwise than as set forth in the claims, but what I claim is:

1. In a drawing frame having upper and lower drawing rolls and associated top roll units, that improvement which comprises a readily detachable tension device for each top roll unit comprising an independent frame member, bearing blocks mounted on said frame member and engaging said upper and lower drawing rolls at the rear of said rolls and coacting with said drawing rolls to entirely support said frame member and tension device, said frame member having an upper forward projection, a bell-crank lever pivotally mounted at the upper end of said forward projection and having a depending arm and a rearwardly-extending arm, a pressure-applying device for said top roll unit which is mounted at the free end of said depending lever arm, and a spring effective to apply pressure through said rearwardly-extending lever arm, said depending lever arm and said pressure-applying device to said top roll unit, and said spring being also effective to apply forward pressure through said bearing blocks to said drawing rolls and to thereby hold said frame member and tension device in operative position in said drawing frame.

2. In a drawing frame having upper and lower rotated drawing rolls and associated top roll units, that improvement which comprises a tension device for each top roll unit comprising a frame member, means to support said frame member behind said drawing rolls, said frame member having a forward projection, a bell-crank lever pivotally mounted at the outer end of said forward projection and having a depending arm and a rearwardly-extending arm, a pressure-applying device for said top roll unit mounted at the free end of said depending lever arm, a spring effective to apply pressure through said rearwardly-extending lever arm to said depending lever arm and pressure-applying device and to said top roll unit, a traverse rod, and a part clamped

to said rod which positions said frame member axially
of said drawing rolls.
